UNITED STATES PATENT OFFICE.

FREDERIC L. WARD, OF OXFORD, MICHIGAN.

HYDRAULIC EXCAVATING APPARATUS.

Application filed April 11, 1927. Serial No. 182,892.

The invention relates to hydraulic excavating apparatus of that type particularly adapted for the removal of sand and gravel from deposits under a body of water. This 5 application is a continuation in part of an application filed by me November 24, 1924, bearing Serial No. 751,973.

It is usual to employ for this apparatus 10 centrifugal pumps connected with a suction conduit through which the material is conveyed. This is objectionable in that all of the sand and gravel aggregate must pass through the pump having an abrasive effect thereon. Another method is to use an injector nozzle for imparting velocity to the 15 liquid stream within the conduit thereby avoiding passing the material through the pump. However, with both methods the percentage of liquid to solid material passing through the conduit is very high and the 20 conveyance of the material is dependent upon the velocity of the stream.

It is a primary object of the present invention to increase the percentage of solid 25 to liquid material carried through the conduit thereby increasing capacity and reducing cost of operation.

It is a further object to utilize the hydrostatic pressure of the body of water beneath 30 which the bed is located for positively lifting the material rather than depending upon the velocity of the flowing stream.

With these and other minor objects in 35 view the invention consists in the method and apparatus as hereinafter set forth;

In the drawings:

Figure 1 is a side elevation of the apparatus.

Figure 2 is a longitudinal section through 40 a portion of Figure 1.

Figure 3 is a similar view showing a modified construction.

To effectively use the hydrostatic pressure 45 of the water for lifting the material, it is necessary, first to insert the suction conduit into the material to sufficient depth to substantially seal around the same; second to reduce the back pressure within the conduit so that the external pressure will become effective. This is preferably accomplished by the use of a substantially vertically arranged suction conduit A depending from the inclined conduit B through which the material is conveyed upward above the surface of the water. The conduit A is preferably of substantially uniform diameter throughout its

length and is also preferably provided with an annular series of jets C for loosening the material in the bed thereby facilitating the lowering of the conduit thereinto. Adjacent to the point of juncture of the conduit A and the conduit B there is arranged an ejector comprising a Venturi tube D and a nozzle E for directing a stream centrally thereinto. The throat of the venturi is of a diameter equal to the internal diameter of the conduit A so that any material entering through the latter can pass through said throat. Also, the parts are so proportioned and arranged that all back pressure is removed from the entrance end of the conduit A thereby making the external hydrostatic pressure effective.

The nozzle E is preferably supplied with water under high pressure conveyed thereto 75 through a conduit F and return bend G. It is not, however, absolutely necessary that water should be used as any fluid under sufficient pressure may be utilized in the jet for imparting velocity to the liquid column 80 and eliminating back pressure in the suction conduit. As shown in Figure 3, I have combined with the water nozzle E an inner nozzle H for compressed air. This will assist in developing a high pressure jet and more 85 economically than by the use of water alone. The jet C surrounding the suction conduit may be supplied with fluid through the hollow wall of said conduit which may be connected by a conduit I with the supply conduit G.

With the construction as described, in operation the conduit B is lowered by suitable means not shown until the mouth of the conduit A rests upon the bed and the weight 95 of the apparatus together with the action of the jet C will then cause the conduit A to penetrate the bed to a considerable depth. This will substantially seal around the outside of the conduit A so that the hydrostatic 100 pressure acting on the loosened material will force this bodily upward through the conduit. As the material at the mouth is removed more material from the surrounding wall of aggregate will become loosened and fall in thereby maintaining the seal. The conduit may also be moved laterally into new material as fast as it becomes exhausted at any one point.

Where air is introduced through the nozzle 110 H to supplement the water from the nozzle E and passes upward through the inclined con-

duit B there is danger of separation between the air and water, the air rising to the top and the water remaining below. This can be avoided by a spiral twisting or rifling of 5 the conduit indicated at J which by inducing a whirling or centrifugal action will keep the two fluids commingled. This, however, forms the subject matter of another application for patent and will therefore not 10 be described further in detail.

In the complete operation of the apparatus the aggregate which is forced upward through the conduit A by hydrostatic pressure enters the conduit B where it is in the 15 path of the pressure from the jets E and H. This will continue to carry the mass upward and with a high percentage of solid material to the liquid employed.

What I claim as my invention is:

20 1. The method of excavating and removing sand and gravel aggregate from sub-aqueous deposits which consists in inserting a suction conduit to a sufficient depth within the mass to maintain a substantial seal 25 around the mouth thereof and reducing the back pressure within said conduit whereby the material is lifted therein by the hydrostatic pressure of the overlying body of water.

30 2. The method of excavating and removing sand and gravel aggregate from sub-aqueous deposits which consists in inserting a suction conduit to a sufficient depth within the material to maintain a substantial seal 35 around the mouth thereof and in injecting fluid into the lower portion of said conduit in an upward direction to remove the back pressure and to permit the material to be lifted within said conduit by the hydrostatic pressure of the overlying body of water.

35 3. The method of excavating and removing sand and gravel aggregate from sub-aqueous deposits which consists in inserting the lower end of a suction conduit into the 45 mass to a sufficient depth to substantially seal around the mouth thereof, directing high pressure fluid jets around the mouth of said conduit into the material to loosen 50 the same and to assist in the insertion of the conduit and in injecting fluid into the lower portion of said conduit under sufficient pressure to substantially eliminate the back hydrostatic pressure within said conduit 55 whereby the material is lifted within said conduit by the hydrostatic pressure of the overlying body of water.

40 4. The method of excavating and removing sand and gravel aggregate from sub-aqueous deposits which consists in inserting a suction conduit within the material and loosening the material around the mouth of 60 said conduit to maintain a substantial seal by said loosened material and in ejecting the fluid from the lower portion of said con-

duit in an upward direction to remove the back pressure whereby said loosened material is lifted within the conduit by the hydrostatic pressure of the overlying body of water and with a relatively low percentage 70 of fluid content.

5. An apparatus for excavating and removing sand and gravel aggregate from sub-aqueous deposits comprising a conduit adapted to be lowered from the surface of the water to bury its lower end in the aggregate and to a sufficient depth to maintain a substantial seal of the material around its mouth and a fluid operated upwardly directed ejector in the lower portion of said 75 conduit for substantially removing the hydrostatic back pressure.

6. In an apparatus for excavating sand and gravel aggregate from sub-aqueous deposits comprising a conveyor conduit adapted to be lowered from the surface of the water into an inclined position, a mouth portion for said conduit extending substantially vertically from the lower end thereof and adapted to be buried in the material to be removed and a fluid operated upwardly directed Venturi ejector in said conduit the throat of said venturi being not less in diameter than said mouth.

7. In an apparatus for excavating sand and gravel aggregate from sub-aqueous deposits comprising a conveyor conduit adapted to be lowered from the surface of the water into an inclined position with its lower end adjacent to the deposit, a substantially vertical downward extension of said conduit adapted to be buried in the material and a fluid operated upwardly directed Venturi ejector in the lower portion of said inclined conduit having its throat not less 100 in diameter than the mouth of said vertical portion.

8. In an apparatus for excavating sand and gravel aggregate from sub-aqueous deposits comprising a conveyor conduit adapted to be lowered from the surface of the water into an inclined position and provided at its lower end with a substantially vertical downward extension, said extension being buried in the material and being of substantially uniform diameter and an upwardly directed fluid operated Venturi ejector in the lower portion of said inclined conduit and having its throat not less in diameter than the mouth of said vertical portion.

9. In an apparatus for excavating sand and gravel aggregate from sub-aqueous deposits comprising a conveyor conduit adapted to be lowered into an inclined position from the surface of the water, the lower end of said conduit being provided with a substantially vertically extending portion adapted to be buried in the material, said vertical portion being of substantially uniform diameter and being provided with fluid 125

jets for loosening the material in which its mouth is buried and an upwardly directed fluid operated Venturi ejector in the lower portion of said inclined conduit having its 5 throat not less in diameter than the mouth of said conduit.

10. In an apparatus for excavating sand and gravel aggregate from sub-aqueous deposits comprising a conveyor conduit adapted to be lowered from the surface of the water into an inclined position, a fluid jet nozzle at the lower end of said conduit directed upwardly thereinto, a fluid supply conduit for said nozzle extending downward 15 from the surface of the water, a Venturi tube within said conduit above said nozzle and a downward extension connecting into said conveyor conduit in advance of said Venturi tube, said extension being substantially 20 vertical and of substantially uniform diameter and being adapted to have its lower end buried in the material to be removed.

11. In an apparatus for excavating sand and gravel aggregate from sub-aqueous deposits comprising a conveyor conduit adapted to be lowered from the surface of the water into an inclined position, a fluid jet nozzle at the lower end of said conduit directed upwardly thereinto, a fluid supply conduit for said nozzle extending downward 25 from the surface of the water, a Venturi tube within said conduit above said nozzle and a downward extension connecting into said conveyor conduit in advance of said Venturi tube, said extension being substantially 30 vertical and of substantially uniform diameter and being adapted to have its lower end buried in the material to be removed, and fluid jets directed downward from the lower end of the vertical extension of said conduit, 35 said jets being supplied from the source of fluid supply for the Venturi jet.

In testimony whereof I affix my signature.
FREDERIC L. WARD.
